UNITED STATES PATENT OFFICE.

RICHARD LE FEUVRE, OF SPOKANE, WASHINGTON.

FLUE CLEANER.

Application filed April 8, 1924. Serial No. 764,977.

To all whom it may concern:

Be it known that I, RICHARD LE FEUVRE, a citizen of the United States, residing at Spokane, in Spokane County, and State of Washington, have invented certain new and useful Improvements in Flue Cleaners, of which the following is a specification.

The present invention relates to improvements in flue cleaners especially adapted for use in scraping or cleaning soot from the walls of chimneys or flues and especially designed for use in connection with the cleaning of chimneys or flues of dwelling houses.

The primary object of the invention is the provision of a gravity actuated device which is comparatively inexpensive in cost of production, is durable, which may be manipulated with facility and convenience by unskilled labor, and which is capable of adjustment for use in various sizes of chimneys for thoroughly cleaning or scraping accumulated soot from the walls or linings of chimneys.

While I have illustrated a cleaner as used in connection with the customary square chimney, it will be understood that the device is capable of use with angular chimneys of other shapes, the walls of which may be cleaned in pairs simultaneously on the gravity or downstroke of the device. Due to its weight and size the device may be manipulated with facility and hauled up manually after a downward movement in customary manner for chimney cleaning.

The invention consists in certain novel combinations and arrangements including a laterally extensible and contractile scraping cage, with means for securing and retaining a stationary adjustment of the scraping blades of the cage, together with means whereby the scraping blades may be manually controlled while the device is being operated. And the invention further consists in certain details of construction as will hereinafter be more fully set forth and claimed.

In the accompanying drawings I have illustrated one complete example of the physical embodiment of my invention where-
50 in the parts are combined and arranged according to the best mode I have thus far devised for the practical application of the principles of my invention.

Figure 1 is a perspective view of the chimney cleaner embodying my invention.

Figure 2 is a sectional view at the top of

a chimney showing the cleaner therein and in operative relation thereto.

Figure 3 is a view in side elevation of the cleaner in operative position, and in dotted lines showing the cage contracted.

For convenience of illustration I have shown a portion of a chimney C having a flue lining L within its walls from which the soot is cleaned by the device of my invention, said device being actuated by gravity for a downward or working movement through the chimney. By contact with the walls, in pairs, of the chimney, or with opposite faces of the lining, the soot is scraped off and permitted to fall to the bottom of the flue or chimney from whence it may be removed, and after the downward or working movement the device is hauled up again to the top of the chimney, and these movements repeated as required.

The invention involves the utilization of a laterally extensible and contractile cage made up of metal pieces and preferably of rectangular shape. At the top of the cage an upper cross head 1 is provided and a complementary bottom cross head 2 is connected therewith. Between these cross heads intermediate cross bars 3 and 4 are utilized, the cross heads and cross bars being parallel and the cross heads and cross bars respectively being adjustable toward and away from each other. At their lower edges the cross bars are fashioned with cutting or scraping blades 5 which are designed to 80 scrape the walls or flue lining as the cage is permitted to move downwardly to remove soot or other accumulation therefrom.

The cross heads and cross bars are connected by a toggle arrangement, and the ends of the heads and bars are bent or flanged as at 6 for pivotal connection with the toggle members.

The toggle members comprise two pairs of upper links as 8 and two pairs of lower links as 9, the respective pairs of links each having a pivotal connection at 10 to a cross head and the diverging ends of the links of all the pairs being pivoted to the intermediate scraper bars. It will thus be apparent that the cage may be extended and contracted both laterally and in vertical direction. The scraper bars however in addition to their pivotal supports 10 are provided with retaining pins 11 which rigidly connect them to the diverging ends of the two pairs of upper links of the toggle connection, in

order that the scraper bars may present a rigid structure for contact with the flue lining or chimney wall, and remove the soot therefrom.

5 Between the upper and lower cross heads of the cage a diagonally extending, central draw bar 12 is located, which bar is rigidly secured to the lower cross head with a hooked end 13 therebelow, and passes 10 through a hole 14 in the upper cross head of the cage. Above the upper cross head an eye 15 is fashioned on the draw bar.

For laterally expanding the scraper cage a draw rope 16 is secured to the eye 15 of 15 the draw bar, and it will be apparent that by pulling on the rope the bar may be drawn upwardly through the hole 14 bringing the lower cross head nearer to the upper cross head. This action causes the diverging ends 20 of the toggle links to swing outwardly carrying with them the intermediate scraper bars, 3 and 4, and the scraper bars are thus manually controlled.

25 The scraper cage is normally held expanded laterally by tension of the spring 17, which at its lower end is anchored by a hook 18 to the lower cross head, and has connected to its upper end a take-up chain 19, which in turn is provided with a spring 30 hook 20 which may be snapped in the eye 21 of the upper cross head. The length of the chain between its hook 20 and the spring may be varied to vary the tension of the 35 spring and to vary the relative adjustment of the upper and lower cross heads. By means of the spring and its connection the lateral-expansion of the cage may be adjusted and a resiliently applied outward pressure on the scraper blades is assured to 40 hold them in operative contact with the surfaces to be scraped.

To enhance the action of gravity on the cage a suitable weight 22 is suspended by its 45 eye-bolt 23 and the yoke 24 on the lower cross head from the cage, said weight supplying an adequate load to insure a positive action of the scraper bars on the surfaces scraped as the cage moves downwardly.

50 The cage is suspended and supported and hauled up from the bottom of the chimney by manual power applied to the rope 25, at one end of which a chain 26 is secured, and the chain is connected to the yoke 27 fixed to the upper cross head. By means of a 55 snap hook 28 on the eye 15 at the upper end of the draw rod, the cage may be set to a predetermined, limited lateral expansion.

60 Thus, as will be apparent, the weight by its suspended load, tends to separate the two cross heads, when the upper one of the two is supported or suspended from the rope 25, but by catching the snap hook 28 in a selected link of the chain 26, the load 65 is suspended from the rope 25 through its

chain 26 hook 28, draw bar 12 and the lower cross head 2, and the cage is thus prevented from contracting laterally.

If this limited or positive adjustment is not required the snap hook is disconnected, as in Figure 1, and the operator of the device, by grasping the main rope 25 in one hand and the draw rope 16 in the other hand, the device may be lowered down through the chimney with the two scraper bars engaging opposite walls of the chimney. The draw rope 16 may be manipulated, or held stationary, as required to maintain the proper scraping contact of the scraper bars with the chimney walls. After the cage has been lowered, it is hauled up by manipulation of rope 25 to the chimney top, and the cage may again be lowered if necessary to scrape over the same surfaces, until these walls are cleaned. When used in a rectangular chimney, the cage is then turned at right angles in order that the scrapers may operate on the second pair of chimney walls for cleaning or scraping them, and the performance is repeated until satisfactory results have been attained.

Having thus fully described my invention what I claim as new and desire to secure by Letters Patent is

1. The combination in a chimney cleaner with a pair of spaced cross heads and a lift rope attached to one of them, of a pair of intermediate scraper bars, pairs of toggle links pivotally connected to said heads and having a pivotal connection with said scraper bars, a weight suspended from the lower cross head, and means for transferring the load of the weight from said device to said lift rope.

2. The combination with a laterally extensible cage including a lower cross head, an upper crosshead, and a pair of scraper bars, of a suspended weight connected to the lower cross head, a draw bar fixed to the lower cross head and passed through an opening in the upper cross head, a flexible connection to said upper crosshead for suspending the cage, and means for engaging said draw bar at selective points with said flexible connection.

3. The combination with upper and lower cross heads, intermediate scraper bars, and toggle links connecting said heads and bars, of a weight suspended from the lower cross head and a lift rope having a chain connection to the upper cross head, a draw rod having one end fixed to the lower cross head and passed through an opening in the upper cross head, a spring anchored at one end to the lower cross head, and a chain connected to said spring for selective engagement with the upper cross head.

In testimony whereof I affix my signature,

RICHARD LE FEUVRE,
